US0D1074251S

(12) United States Design Patent (10) Patent No.: US D1,074,251 S
(45) Date of Patent:  *May 13, 2025

(54) COMBINED TRAY AND TABLE

(71) Applicant: Hugh O'Reilly, Niagara Falls, NY (US)

(72) Inventor: Hugh O'Reilly, Niagara Falls, NY (US)

(73) Assignee: Hugh O'Reilly, Niagara Falls, NY (US)

(*) Notice: This patent is subject to a terminal disclaimer.

() Term: 15 Years

(21) Appl. No.: 29/786,215

(22) Filed: May 29, 2021

(51) LOC (15) Cl. 06-04

(57) CLAIM

The ornamental design for a combined tray and table as shown and described.

DESCRIPTION

FIG. 1 is a side perspective view of a combined tray and table, showing my new design;

FIG. 2 is a front perspective view thereof;

FIG. 3 is a bottom view shown in an alternate position;

FIG. 4 is a top perspective view of FIG. 1; and,
FIG. 5 is a perspective view of a combined tray and table shown in use.

In the drawings, the broken lines are for the purpose of illustrating environment only, and form no part of the claimed design.

1 Claim, 3 Drawing Sheets
